COMBINED TURBINE AND JET PROPELLED ENGINE FOR AIRCRAFT

Bernard Stanley Lynn, Palo Alto, Calif., and Ivan H. Driggs, Bethesda, Md.

Application February 21, 1950, Serial No. 8,042

Term of patent 3½ years

(Cl. D71—1)

To all whom it may concern:

Be it known that we, Bernard S. Lynn and Ivan H. Driggs, citizens of the United States, residing at Palo Alto, California, and Bethesda, Maryland, respectively, have invented a new, original, and ornamental Design for a Combined Turbine and Jet Propelled Engine for Aircraft, of which the following is a specification, reference being had to the accompanying drawings, forming a part hereof.

Fig. 1 is a perspective view of a combined turbine and jet propelled engine for aircraft, showing the new design;

Fig. 2 is a top plan view of the subject engine;

Fig. 3 is a front elevational view thereof;

Fig. 4 is a bottom view; and

Fig. 5 is a rear elevational view thereof.

The dotted lines shown in the several drawing figures are for illustrative purposes only.

We claim:

The ornamental design for a combined turbine and jet propelled engine for aircraft, as shown and described.

BERNARD STANLEY LYNN.
IVAN H. DRIGGS.
